UNITED STATES PATENT OFFICE.

JOSEPH JOHN NELIS, OF BROOKLYN, NEW YORK, ASSIGNOR TO POWER SPECIALTY COMPANY, OF NEW YORK, N. Y., A CORPORATION OF NEW YORK.

SUPERHEATER BOILER.

Application filed January 29, 1925. Serial No. 5,420.

My present invention relates to horizontal return tubular boilers, and particularly to a battery of such boilers located above a common combustion chamber, and the object of 5 my invention is to provide improved means at the rear end of the boilers for effecting a proper distribution of the heating gases along the different boilers and among the return flues or tubes of the different boilers; 10 and to provide for a better disposition of, and a better distribution of the heating gases over, steam superheater elements located at the rear ends of the boilers.

The various features of novelty which 15 characterize my invention are pointed out with particularity in the claims annexed to and forming a part of this specification; but for a better understanding of the invention, however, its advantages and specific objects 20 attained with its use, reference should be had to the accompanying drawings and descriptive matter in which I have illustrated a preferred embodiment of my invention.

Of the drawings:

25 Fig. 1 is a sectional elevation;

Fig. 2 is a plan view with parts broken away and in section; and

Fig. 3 is a rear elevation with parts broken away and in section.

30 The boiler installation illustrated in the drawing comprises a battery of horizontal return tubular boilers A arranged side by side, a housing B for the boilers including a common combustion chamber C underlying all of the boilers adjacent their front ends, and a combustion chamber extension C' running to the rear of the boilers where it communicates through ports E' and E² in a baffle wall E with a chamber D. The chamber D communicates adjacent its upper end with the return flues or tubes A' of the boilers, and is advantageously extended downward a considerable distance below the level of the bottom wall B' of the combustion chamber extension C' to provide space for the superheater elements H.

35 The steam generated in the boilers passes to the inlet header G of the superheater through a pipe F. The inlet header G and the outlet header I of the superheater are 40 horizontally disposed and located externally of the boiler housing at the rear end of the latter. The elements H are advantageously of the well known Foster type comprising 45 tubes surrounded by externally corrugated

cast iron casings. The individual elements H are connected in pairs at their upper ends by return bends or coupling parts H', located in or on the top wall of the chamber D and advantageously accessible from the exterior of the boiler housing. Of each pair of elements thus connected, one has at its lower end a transversely extending portion H² connected to the header G, and the other has at its lower end a transversely extending portion H³ connected to the outlet header I. The transverse end portions H² and H³ extend through the rear wall of the chamber D. The latter is advantageously provided with suitably disposed clean out doors d adjacent its lower edge. The headers G and I are advantageously mounted on pillars K and secured in place by suitable clamping yokes K'.

45 The baffle wall E extends from the roof B² of the boiler housing proper to the floor B'. While I have referred to the baffle wall E as a continuous structure, as it may be, in the construction shown it is formed of sections one at each side of each boiler A, each 50 section being formed with leg or pier portions e one at each side of the corresponding port E'. The ports E² are located between the adjacent leg portions e of adjacent baffle wall sections and each of these ports extends 55 from the combustion chamber floor B' to the under side of the boiler A above.

55 The ported baffle wall between the combustion chamber and the chamber D tends to a good distribution of the heating gases 60 across the width of the combustion chamber C and its extension C', and over the superheater elements along the length of the superheater as a whole. In particular, this ported baffle wall avoids the tendency which exists 65 when said wall is not employed for the heating gases to leave the combustion chamber extension C' in concentrated streams through the spaces between the boilers A and immediately beneath the housing roof portion 70 B². The improved distribution of the heating gases thus obtained, increases the effectiveness of the portion of the boiler heating surface formed by the boiler drums as well as the portion formed by the walls of 75 the return flue passages, and also increases the effectiveness of the superheating surface.

80 The boiler arrangement disclosed was primarily devised, and is especially suitable for use in shallow draft river steam boats,

but the invention is obviously not limited to such use.

Having now described my invention, what I claim as new and desire to secure by Letters Patent, is:

- 5 1. The combination with a plurality of side by side horizontal boilers with internal return flue passages and a housing providing a common combustion chamber beneath the 10 boilers and a chamber at the rear end of the boilers through which the heating gases pass from the combustion chamber into the return flue passages of the boilers, of a baffle wall between said chambers formed with a plurality of distributed gas ports connecting the 15 chambers.
- 20 2. The combination with a plurality of side by side horizontal boilers with internal return flue passages and a housing providing a common combustion chamber beneath the 25 boilers and a chamber at the rear end of the boilers through which the heating gases pass from the combustion chamber into the return flue passages of the boilers, of a baffle wall between said chambers formed with a plurality of distributed gas ports connecting the 30 chambers, and a superheater located in the last mentioned chamber.
- 35 3. The combination with a plurality of horizontal return tubular boilers with internal return flue passages and a housing providing a common combustion chamber beneath the boilers and a chamber at the rear end of the boilers communicating at its upper 40 ends with the return flue passages of the

boilers and extending below the adjacent portion of the combustion chamber, of a wall between said chambers formed with distributed gas ports connecting the chambers, and a superheater located in said second 45 chamber and comprising vertical tube elements arranged in a series extending horizontally for substantially the full width of the boiler.

4. The combination with a plurality of horizontal return tubular boilers with internal return flue passages and a housing providing a combustion space beneath the boilers and a chamber at the rear end of the boilers communicating at its upper ends 50 with the return flue passages of the boilers and extending below the adjacent portion of the combustion space, a wall between said space and chamber formed with distributed 55 gas ports connecting said space and chamber, and a superheater located in said chamber and comprising vertical tube elements arranged in a series extending substantially the full width of the boiler, said elements being connected in pairs at their upper ends 60 and being provided at the lower ends with rearwardly extending portions projecting through the rear wall of said chamber, and superheater headers at the rear of the boiler housing to which said projecting ends are 65 connected.

Signed at New York city, in the county of New York, and State of New York, this 24th day of January, A. D., 1925.

JOSEPH JOHN NELIS.
